UNITED STATES PATENT OFFICE.

WILLIAM T. IRWIN, OF BONUS, ILLINOIS.

CORN-HUSKING MACHINE.

SPECIFICATION forming part of Letters Patent No. 566,181, dated August 18, 1896.

Application filed February 8, 1896. Serial No. 578,571. (No model.)

To all whom it may concern:

Be it known that I, WILLIAM T. IRWIN, a citizen of the United States, residing at Bonus, in the county of Boone and State of Illinois, have invented certain new and useful Improvements in Corn-Husking Machines, of which the following is a specification.

The object of the invention is to create a forcible feed to the ears of corn in passing 10 down the husking-rolls.

The further object of this invention is to insure the ears of corn engaging the husking-rolls and causing them to descend endwise.

In the accompanying drawings, Figure 1 is 15 a plan view of a portion of a corn-husking machine in which the husking-rolls have been omitted for clearness. Fig. 2 is an elevation of the delivery end of a corn-husking machine. Fig. 3 is a side elevation. Fig. 4 is 20 a vertical lengthwise section on dotted line *a*, Fig. 1. Fig. 5 is a side elevation of the adjustment of the upper end of the endless carrier.

The main frame of the machine consists of 25 the lengthwise side beams 1, held separated by the cross-beam 2, and vertical beams 3 connect the side beams with the base-sills of the frame. Between the sides of the main frame are located three sets of husking-rolls 30 4, of any suitable construction, which are revolved in the direction indicated by the arrows shown in Fig. 2. These rolls are set on an incline, the delivery ends being lowest. Near the upper ends of the husking-rolls and 35 over the same is located a transverse shaft 5, and supported in boxes 6. (Shown at Fig. 5.) These boxes are fitted to move in the curved slot 7, and a set-screw 8 limits the descent of the boxes. This shaft has a connection with 40 bars 9 and 10, located outside of the main frame, their other ends being pivotally supported by stub-shafts 11 and 12, thereby supporting the shaft 5 in a pivoted frame.

The stub-shaft 12 has a sprocket-wheel 13 45 secured thereto and is connected by a linked belt to the driving power of the machine. A smaller sprocket-wheel 14 is secured to this stub-shaft, and is connected by a linked chain 15 with a sprocket-wheel 16, secured to the 50 transverse shaft 5, so that the rotary movement imparted to the sprocket-wheel 13 will be transmitted to the transverse shaft 5.

The transverse shaft 5 supports three frames of like construction. A description of one will suffice for all. Upon the shaft are 55 located two couplings 17 and 18, having a swiveled or pivotal movement in connection therewith. To these couplings are secured tubular bars 19. An extensible frame has a connection with the tubular bars and consists of a shaft 20, supported in boxes 21, from which extend screw-threaded rods 22. These rods enter the ends of the tubular boxes, and a cross-bar 23, connecting the rods, is held in place by nuts 24, placed on each side of 60 the cross-bar. A wheel 25 is secured to the shaft 20, and a sprocket-wheel 26 is secured to the transverse shaft 5. These sprocket-wheels are connected by a linked belt 27, from which at proper intervals extend teeth 65 28. (Shown at Figs. 2 and 4.) By means of the nuts 24 the extensible frame can be adjusted to take up any slack in the chain belt. The ends of the shaft 20 are supported in a yoke 29, from which extends a screw-threaded rod 70 75 30, passing through a transverse beam 31, receiving a nut 32 on the upper side of the beam.

The chain belt 27 is located over the center between a pair of husking-rolls. Its lower 80 end can be vertically adjusted by means of the nut 32. The ears of corn are dropped onto the husking-rolls at their upper ends, and the teeth 28 of the chain belt engage them, carrying them along the husking-rolls, 85 and after being husked force them free of the rolls at their lower ends. It will be noticed that each pair of husking-rolls have an endless chain belt provided with teeth, their lower ends made independently self-adjustable, while their upper ends are connected 90 to the transverse shaft 5, and this shaft is vertically movable, as before described.

Should the ears of corn accumulate under the transverse shaft, it will raise, and when 95 the accumulation has moved on it will drop to its normal position. Should two ears of corn ride each other, the teeth of the chain belt will carry the topmost ear with it until it is free of the bottom ear, when both ears 100 will be forced along the husking-rolls, and by this means all clogging of the husking-rolls is prevented.

Between each pair of husking-rolls is lo-

cated a fender 33, extending in the lengthwise direction of the rolls, their upper ends supported by the transverse shaft by means of the hook 34. To this fender are secured 5 transverse strips of leather 35, those of one fender located between those of the other fender. By means of these fenders the ears of corn are thrown to either side in order that they may be operated upon by the husking- 10 rolls. The lower ends of these fenders are adjustably supported by the vertical screw-threaded rod 36, passing through the transverse bar 31, receiving a nut 37 on the upper end.

15 To the bar 10 is secured a tightener 38 for the chain belt 15.

I claim as my invention—

In a corn-husking machine, the combina-

tion of two or more pairs of husking-rolls, an endless carrier located between the rolls of each pair for forcing the ears along the rolls, a transverse driving-shaft, a frame for each carrier consisting of two tubular rods extending in the lengthwise direction of the carrier, a U-shaped frame supporting a wheel over 25 which the carrier passes, the arms of the frame entering the ends of the tubular rods being screw-threaded and nuts placed upon the arms, a cross-bar located at the ends of the tubular rods, and a drive-wheel supported 30 by the driving-shaft imparting movement to the carrier.

WILLIAM T. IRWIN.
